UNITED STATES PATENT OFFICE.

PETER J. FITZGERALD, OF HYDE PARK, MASSACHUSETTS.

VAPOR-BURNER.

SPECIFICATION forming part of Letters Patent No. 423,747, dated March 18, 1890.

Application filed June 15, 1889. Serial No. 314,437. (No model.)

To all whom it may concern:

Be it known that I, PETER J. FITZGERALD, a citizen of the United States, residing at Hyde Park, in the county of Norfolk and State 5 of Massachusetts, have invented a new and useful Improvement in Vapor-Burners, which improvement is fully set forth in the following specification and accompanying drawings.

My invention consists of a vapor-burner 10 of novel construction, as will be hereinafter set forth, and the features thereof definitely claimed.

Figure 1 represents a partial top view and 15 partial horizontal section of a vapor-burner embodying my invention. Fig. 2 represents a partial side elevation and partial vertical section thereof.

Similar letters of reference indicate corresponding parts in the two figures.

20 Referring to the drawings, A designates a burner embodying my invention, the same consisting of a vaporizing-chamber B, of the form of an annulus, with a vertical partition or wall C therein, said chamber having an inlet D and outlet E. Depending from the 25 chamber B, and connected with the same at the outlet E, is a pipe F, to which is attached a valve-chamber G.

H designates a tube, which rises from and 30 is connected with the valve-chamber G, and passes within the inner wall of the chamber B to a point above said chamber, where it has attached to it the pipes J, the outer ends whereof are provided with burners K. In the 35 tube H are openings L for the admission of air thereto, and above the same are openings M, as jets for burning vapor thereon.

The operation is as follows: Hydrocarbon 40 or other vaporizable fluid is admitted into the chamber B, and some of the same primarily escapes at the openings M, where it is ignited, so as to heat the chamber B and the pipes J. The fluid subsequently entering said hot chamber is vaporized in its passage through 45 the same, and then passes through the tube F, valve-chamber G, and tube H, the supply of fluid and vapor being regulated by a screw-valve N in said chamber. Owing to the perforations, some of the vapor escapes from said tube

H, and being ignited heats the chamber B and 50 the pipes J, as well as the upper part of said tube H, the pipes J extending from the tube H over the space between the latter and the inner wall of the chamber B, said tube being closed at top and constituting a retort to receive the 55 partially-vaporized fluid from said chamber, the degree of vaporization increasing as the vapor passes through said retort or tube H and the pipes J, the vapor escaping at the burners K, where it is consumed. Owing to 60 the partition or wall C in the chamber B, the hydrocarbon fluid primarily and the vapor resulting traverse said chamber before they reach the exit E, so as to be subjected to a large heating surface and action. It will be 65 noticed that the pipes J are in contact with the upper wall of the chamber B, and are set into said wall, whereby the temperature of said pipes J is increased, thus assisting in causing effective vaporization. Should the 70 flame of the burners be extinguished by drafts, it will be relighted by the jets of flame at the openings M of the tube H.

The burner as constructed will be found to be practicable, may be easily cleaned, avoids 75 smoke, and permits the use of cheap or low grades of hydrocarbon fluid, such as naphtha.

The burner herein shown and described forms part of the subject-matter of an application filed by me of date June 19, 1888, and 80 bearing Serial No. 277,554, but is not claimed therein.

Having thus described my invention, what I 85 claim as new, and desire to secure by Letters Patent, is—

1. A vapor-lamp consisting of an annular vaporizing-chamber with a vertical partition therein, an inlet in said chamber on one side of said partition and an outlet on the other side thereof, a valve-chamber connected with 90 said annular chamber by a pipe, a tube rising from said valve-chamber and passing within the inner wall of said annular chamber, and pipes leading from said tube and having burners thereon, said tube having air-openings therein, said parts being combined substantially as described.

2. A vapor-lamp consisting of an annular

vaporizing-chamber having a vertical partition therein, an inlet in said chamber on one side of said partition and an outlet on the other side thereof, a valve-chamber communicating with said annular chamber, and a tube leading upward from said valve-chamber and having pipes communicating therewith and provided with burners, said tubes having the

air-inlet openings L and the vapor-openings M, said parts being combined substantially as described.

PETER J. FITZGERALD.
